CASING FOR MOULDABLE FOOD PRODUCT EXTRUDER

Gorden Edward Sloan, 345 Carousel Place, Anaheim,
Calif. 92805, and Floyd Vernon Edwards, 2526 S.
Rita Way, Santa Ana, Calif. 92704

Filed May 21, 1969, Ser. No. 17,263

Term of patent 14 years

Int. Cl. D15—12
U.S. Cl. D55—1

FIG. 1 is a perspective view of casing for mouldable food product extruder showing our new design;

FIG. 2 is a front elevational view thereof;

FIG. 3 is a side elevational view thereof as seen from the left of FIG. 2;

FIG. 4 is a top plan view thereof; and,

FIG. 5 is a bottom plan view thereof.

We claim:

The ornamental design for a casing for mouldable food product extruder, substantially as shown.
